UNITED STATES PATENT OFFICE.

SVEN MELCHER MYRTIN, OF STOCKHOLM, SWEDEN.

FLAT SCREEN.

1,027,143.

Specification of Letters Patent.

Patented May 21, 1912.

Application filed August 24, 1910. Serial No. 578,751.

To all whom it may concern:

Be it known that I, SVEN MELCHER MYRTIN, a subject of the King of Sweden, residing at Stockholm, Sweden, have invented 5 certain new and useful Improvements in Flat Screens, of which the following is a specification.

The flat screens hitherto in use are so called suction screens, in which the pulp, 10 *i. e.* cellulose fiber pulped in water, is sucked through the screen plates by membranes which are set in an up and down motion. Such screens possess, however, small capacity for production, besides which the 15 membrane is easily worn out and must be renewed.

The present invention, by which these inconveniences are removed, relates to flat-screens built upon the principle of communicating vessels and in which the pulp moves from below upward and pulsation is 20 effected in the pulp by means of a piston.

The invention consists essentially therein, 25 that the piston, arranged in the channel of the screen opposite the screen-plates, is reciprocated vertically by means of eccentrics on crank-arms, a play existing around such piston between the same and the wall of the channel. This arrangement of the 30 piston has for its object to distribute the thrusts caused by the same in the pulp as uniformly as possible on the whole surface of the screen-plates in order to give a more effective hindrance to the stopping of the 35 screen-plates. This arrangement can be combined with fixed ribs arranged at the lower side of the screen-plates and set obliquely to the direction in which the pulp moves.

40 In the accompanying drawing a flat-screen constructed according to the invention here in question is shown.

* Figure 1 shows the flat-screen looked at from the front, Fig. 2 a vertical cross-section and Fig. 3 the same in plan view.

A tank built on the principle of communicating vessels has a larger chamber, the inlet-chamber 1, and a smaller chamber, the outlet-chamber 2, which together form 50 the communicating vessels and are separated from each other by a screen-plate wall 3. The bottom of the tank is softly rounded off, whereby the motion of the pulp against the screen-plate wall is facilitated.

55 The slits or holes of the latter may be of any suitable shape, and if they are conical,

their smaller opening is in the opposite direction of the motion of the pulp.

The pulp is conducted into the inlet chamber 1 through the upper open end of it and carried off through an overflow 4, which for that purpose is fixed at a proper height above the screen-plate wall 3. In the upper part of the inlet-chamber there is journaled a shaft 5, which is fitted with four eccentrics 6. The eccentric rings have connecting rods 7 hanging straight down. At the end of these connecting rods at right angles to the rods, and consequently at right angles to the current of the pulp there are fitted some wooden or iron plates or pistons 10 fastened by means of nuts 8 and clamp-disks 9; these pistons are reciprocated in the length-direction of the inlet chamber by means of these eccentrics and 70 connecting rods, a play existing around the pistons between the same and the wall of the inlet chamber. When the shaft makes about 150 to 200 revolutions per minute the pistons in their downward motion cause 75 shocks in rapid succession in the liquid. When the eccentricity is about 15 to 20 mm., the lateral motion or stroke of the plates is slight. The eccentrics 6 are best fixed to the shaft 5 in such a way that for example 80 two pistons go up, as the other two go down. Through such an arrangement of the eccentrics a more uniform distribution of power on the shaft is also obtained, besides which the pistons will also to a certain extent balance each other, whereby the 85 consumption of power is reduced. As the movable parts only consist of eccentrics, the machine manifestly moves noiselessly. The separate eccentrics can, if wanted, be provided, with arrangements for varying the eccentricity, so that the latitude of motion of the pistons can be increased or decreased 90 just as required. It is obvious that the flat-screen can be fitted with a smaller or larger 95 number of pistons and eccentrics than four.

As has been said, the pistons are hanging free in the pulp without tightly fitting the walls. The space between the pistons and between the pistons and the walls is arranged 105 in such a manner that the speed of the current and the pulsation of the pulp are in the most favorable proportion to each other. The pistons may however, as is shown in the drawing, be provided with valves 11, 110 which open with the upward motion, whereby the consumption of power is reduced.

The inlet-chamber may also be divided up into two or more sections by means of transverse walls 12, with one or more pistons operating in each section. Close to 5 the wall 13 there is fitted a register 14, which hangs upon rods 15 and may be regulated by means of nuts 16. 17 are lists for guiding the said register. By means of the register the speed of the current of the 10 pulp can be regulated. Fiber knots and other coarse objects can be drawn off now and then by means of a tube 18 fitted in the bottom or end of the apparatus. The apparatus is also provided with one or more 15 cleaning shutters 19, whereby the cleansing of the apparatus takes place. As the screen-plate wall has the wider openings turned upward it is easy to wash them clean, and there is no need of raising it for that 20 purpose.

When the coarser particles, as mentioned, are drawn off through tube 18 a portion of usable fiber follows of course also. To utilize this it is best to arrange in such a manner 25 that the said coarser particles from one or several screens are conducted into a separate screen, of a smaller size than the former, and preferably in the lower part of the inlet chamber, wherefore in that case 30 the flat-screen is fitted with an inlet-valve (not shown) for the pulp in the lower part of the inlet-chamber. Simultaneously pure water is introduced into the lower part of 35 the inlet-chamber. The said particles will thus be subjected to a washing process and the useful fibers separated and passed through the screen-plate wall. In this manner an absolutely continuous operation with 40 regard to both pulp and fouling can thus be carried on with a couple of screens.

In order to increase the effect of the apparatus a number of fixed ribs 20 or such like, is arranged at the lower side of the screen-plates and set obliquely to the direction 45 in which the pulp moves. These operate therefore as a sort of sand catchers in such a manner that, when there is more foul matter in the pulp, this strikes the ribs

and is stopped in its motion and sinks down. The ribs are, in contradistinction to certain 50 other machines, in which fixed ribs are used, fitted close to the screen-plate wall, whereby the liquid close to the latter is kept cleaner. One or more rows of ribs may be used, and the ribs in one row may be arranged in zig- 55 zag against the ribs in an adjoining row.

I claim:—

1. In apparatus of the class described, in combination, a tank, said tank having an inlet chamber and an outlet chamber with- 60 in said inlet chamber and communicating therewith, a screen positioned between said chambers, said inlet chamber being provided with an upwardly extending portion, a shaft, eccentrics carried thereby and pistons supported by said eccentrics and positioned within said upwardly extending portion, whereby rotation of said shaft will reciprocate said pistons in the direction of the length of said portion, said pistons being 65 spaced from one another and from the walls of the tank to provide for play.

2. In apparatus of the class described, in combination, a tank, said tank having an inlet chamber and an outlet chamber with- 70 in said inlet chamber and communicating therewith, a screen positioned between said chambers, a plurality of obliquely set ribs fixed adjacent the lower side of said screen, said inlet chamber being provided with an 75 upwardly extending portion, a shaft, eccentrics carried thereby and pistons supported by said eccentrics and positioned within said upwardly extending portion, whereby rotation of said shaft will recipro- 80 cate said pistons in the direction of the length of said portion, said pistons being spaced from one another and from the walls of the tank to provide for play.

In testimony whereof I have hereunto set 90 my hand in presence of two subscribing witnesses.

SVEN MELCHER MYRTIN.
